COMBINED LITTER CONTAINER AND ADVERTISING DISPLAY DEVICE

Walter Kay, 815 S. 18th St., Arlington, Va. 22202, and
Raymond M. Poelvoorde, Birmingham, Mich.; said
Raymond M. Poelvoorde assignor to said Walter Kay

Continuation-in-part of design application Ser. No.
226,383, Feb. 14, 1972, now Patent No. 229,279,
dated Nov. 20, 1973. This application Mar. 2,
1973, Ser. No. 337,450

Term of patent 14 years

Int. Cl. D20—99

U.S. Cl. D7—191

FIG 1

FIG. 3

FIG. 4

FIG. 1 is a perspective view of the combined litter container and advertising display device in closed position showing our new design;

FIG. 2 is an enlarged perspective view of the open container;

FIG. 3 is a side elevational view of the closed container; and

FIG. 4 is a bottom plan view thereof.

This is a continuation-in-part of design application Ser. No. 226,383, filed Feb. 14, 1972, now design patent No. D. 229,279, dated Nov. 20, 1973.

We claim:

The ornamental design for a combined litter container and advertising display device, substantially as shown and described.
